RAIL BOND

Ernest J. Sabol, Edgewood, Pa.

Application July 11, 1940, Serial No. 344,968

2 Claims. (Cl. 287—20.3)

This invention relates to rail bonds of the stud terminal type that are adapted for installation to the heads of the rails to be bonded, one of the objects being to provide a bond of this type having terminals provided with studs that are solid throughout including their junctions with the terminal heads and which can be installed with substantially the same ease as terminals having the less sturdy hollow studs.

Specific examples of the invention are illustrated by the accompanying drawing, in which:

Figure 1 is a sectional view of a bond embodying the features of the invention;

Figure 2 is a tool adapted for use in the installation of this bond;

Figure 3 is a view similar to Figure 1 but illustrating a second form of bond;

Figure 4 is a tool adapted for use of this second form of bond; and

Figure 5 is a view similar to Figures 1 and 3 but showing a third form of bond.

More specifically, the bond shown by Figure 1 comprises a conductor strand 1 having its ends butt welded to steel terminals each provided with a head 2, a stud 3 and a depression 4 opening from the front of the head 2 and which has a bottom spaced from the back to this head to provide a supply of metal between this bottom and back.

Installation of this bond is effected by the tool shown by Figure 2, the working end 5 of this tool being shaped to fit the depression 4 and functioning, when the head of the tool is hammered, to displace some of the supply of steel between the bottom of the depression 4 and back of the terminal head 2, beyond this back. Since the stud 3 solidly and integrally connects with this back of the head 2, it receives this displaced metal and its volume is increased. In Figure 1 the left-hand terminal is ready for this action while the action has already occurred in the case of the right-hand terminal.

It is to be understood that the steel used in the construction of the terminal head is malleable whereby it can flow into the stud. A sufficient supply of metal is provided between the bottom of the depression 4 and the back of the head 2 so that the supply is never exhausted when oversized rail holes are encountered. The left-hand terminal in Figure 1 shows the appearance of the described terminal prior to installation, while the right-hand terminal shows its appearance after installation.

The depression 4 is shown as having the same

diameter as the diameter of the stud 3, and as being provided with a hemispherical bottom. The flow of the supply of metal from the head into the stud is longitudinal respecting the stud until it encounters considerable resistance by reason of confinement of the outer walls of this stud by the side of the rail hole, whereupon the flow moves radially so as to radially enlarge the stud.

During the installation of this terminal by means of the tool shown by Figure 2, the depression 4 in the terminal head 2 may be said to function in the manner of a cylinder in which the end 5 of the tool works as a piston plastically extruding metal from the head of the terminal 15 into the stud 3. To further this effect, both the sides of the depression 4 and of the tool 5 are made cylindrical, the working face of the end 5 of the tool fitting the bottom of the depression 4.

20 The terminal shown by Figure 3 has a depression, indicated at 6, the side of this depression being cylindrical. The tool shown by Figure 4 has a working end 7 provided with a cylindrical side fitting the cylindrical side of the depression 6, the end of this tool tapering to a flat surface. When this tool is used, its end engages the bottom of the depression 6 and starts a downward flow of metal from the supply between the bottom of this depression and the back of the 25 terminal head, this supply going into the stud integrally connecting with the head. In this Figure 3 the left-hand terminal is shown before installation and the right-hand terminal is shown after installation.

30 In Figure 5 the terminal head is provided with a depression 8 having a cylindrical side and a convex bottom. When this bottom is rendered flat by means of a suitable tool, it forces a supply of metal beyond the back of the terminal head and into the stud. A suitable tool is shown at 9, the tool being, in this instance, permanently retained in the depression 8. This may be done in the case of the other two forms of the bond, or a removable tool may be used in the present instance.

35 It is to be understood that in all cases the stud 3 extends from the terminal head 2 in alignment with the depression formed in this head. Furthermore, the depression is preferably made of the same diameter as the stud 3 although this may not be desirable in every instance. In all instances, the supply of metal displaced from the back of the terminal head and which enters the 40 solid terminal stud, involves the usual principles

attending the plastic flow of metals. That is to say, the metal flows longitudinally until it encounters resistance. It should be further noted that in no instance is it necessary for the tool to pass completely through the terminal head and into the stud so as to weaken the latter by rendering it hollow at its junction with the terminal head.

Attention is called to the frusto-conical shape of the working face of the tool shown by Figure 4. With this shape, during the use of the tool, the metal located centrally of the terminal is placed in motion first before other metal is materially disturbed. The flowing of this central metal into the stud is generally sufficient to fix the latter in place and the restriction of the disturbed metal to this central area provides a terminal head of maximum strength at the junction of the head and stud. This effect is inherent in the terminal construction of Figure 3.

I claim:

1. A rail bond terminal including the combination of a malleable metal head having a depression opening from its front and which has a bottom spaced from the back of said head to provide a supply of malleable metal between said bottom and said back, a tool working in said depression to displace a portion of said supply beyond said back and a solid malleable metal stud

integrally extending from said back in alignment with said bottom to internally receive said displaced portion and be enlarged thereby, said stud being solid throughout after its enlargement by internally receiving said portion, and said depression having the same diameter as that of said stud and being formed with a convex bottom, the bottom of said tool being formed to initially contact the top of said convex bottom and to gradually flatten the same.

2. A rail bond terminal including the combination of a malleable metal head having a depression opening from its front and which has a bottom spaced from the back of said head to provide a supply of malleable metal between said bottom and said back, a tool working in said depression to displace a portion of said supply beyond said back and a solid malleable metal stud integrally extending from said back in alignment with said bottom to internally receive said displaced portion and be enlarged thereby, said stud being solid throughout after its enlargement by internally receiving said portion and the working face of said tool and the bottom of said depression being respectively contoured to provide for initial displacement of a central portion only of said supply into said stud.

ERNEST J. SABOL.
